UNITED STATES PATENT OFFICE.

FRANK A. DONNELLY AND JOHN E. BLANTHORN, OF NEW YORK, N. Y.

FABRIC-CLAMP.

1,106,136.

Specification of Letters Patent.

Patented Aug. 4, 1914.

Application filed April 3, 1913, Serial No. 758,568. Renewed January 13, 1914. Serial No. 811,919.

To all whom it may concern:

Be it known that we, FRANK A. DONNELLY and JOHN E. BLANTHORN, citizens of the United States, residing at New York city, 5 in the county of New York and State of New York, have invented certain new and useful Improvements in Fabric-Clamps, of which the following is a specification.

The object of my invention is to provide 10 a vermin-proof, reliable and indestructible clamp for holding the edges of fabrics subjected to heavy stress and which, while especially adapted for woven wire mattresses, if of general utility for such purposes.

15 It may be generally described as a hard-metal folded clamp with holding lugs or depressions along its margins and attachment holes along its fold and inclosing an edge of fabric, and a soft metal filler which 20 fills all the interstices of the clamp and the inclosed fabric. The clamp is preferably a strip or plate of mild steel with holding conformations symmetrically adjacent to its margins, symmetrical series of attachment 25 holes equally spaced to each side of its axis, and end flaps to one side thereof. The filler is made of an alloy, such as a specially-prepared Babbitt metal.

The plate being properly prepared, either 30 rolled or stamped, it is partly folded along its margin to partially form a clamp; the filler and the fabric edge are entered between the jaws thereof and the partially formed clamp is put through rolls or a press, which 35 completes the fold of the clamp plate and closes its jaws and causes the soft-metal of the filler to flow into and completely fill all the interstices located between the closed clamp-jaws and fabric. Thereafter the end 40 flaps are each folded over an end and upon the body of the clamp. Thus we produce an absolutely vermin-proof and reliable fabric-clamp, indestructible in ordinary use.

In the drawings, Figure 1 is a partial 45 perspective illustrating an end of a clamp holding a woven wire mattress. Fig. 2 is a partial view of a finished clamp. Fig. 3 is a perspective of our preferred form of filler. All the other views, save Fig. 11, 50 are transverse sections of clamps having variant fabric and filler holding means, Fig. 4 showing a partially folded clamp-plate adapted to our preferred filler and Fig. 5

the same variant completely closed, Fig. 6 a partly closed plate adapted to a cylindrical 55 filler and Fig. 7 the same variant closed, Fig. 8 a dove-tail plate partly, and Fig. 9 the same fully closed and Fig. 10 a tongue and groove closed plate enveloping a plate filler. Fig. 11 is a partial view of a clamp plate, 60 ready to be folded. Fig. 12 is a sectional view of a positive fabric-holding means.

In all our variants we provide for attaching the clamp C to a suitable frame or support, by punching series of attachment holes, 65 2, in the clamp plate 1, symmetrically to each side of its axis, so that when it is folded, said holes register. We also form fabric and filler holding means, 3, along the margins of the plate 1.

Figs 8 and 9 illustrate fabric and filler holding means comprising dovetailed channels, 3^a. Fig. 10 illustrates tongue-and-groove fabric and filler retaining means respectively, 3^c and 3^g, and Figs. 6 and 7 70 75 concave groove fabric and filler retaining means, 3^g, both of which can be produced, practically without cost, during rolling, when the plates 1 are manufactured. The dovetail fabric and filler retaining means of 80 Figs. 8 and 9 renders desirable the use of two plate fillers, 4^a. The tongue and groove fabric and filler retaining means of Fig. 10 requires but one plate filler, 4^a; and the twin-groove fabric and filler retaining 85 means of Figs. 6 and 7, will be most satisfactory if a rod filler, 4^c, be used with it.

In all of the above described variants, rivets or some other means of keeping the clamp closed will be necessary in cases where 90 the stiffness of the plate at the fold is insufficient to resist the clamp-opening component of any stress possible to be caused in the fabric f by its proper use. Our preferred variant, illustrated in Figs. 1 to 5 95 inclusive and 12, provides rivets 5 integral with the filler 4^a and set by the same operation which fully closes the clamp. In this variant the holding conformation consists in series of countersunk rivet holes 3^a 100 punched symmetrically adjacent to the margins of the plate 1, and which register when it is folded. By using a die containing holes considerably larger than the punches, or with rounded edges, and punching from the 105 exposed face of the plate, the rivet holes 3^a

can be countersunk and inwardly projecting lips 3^b adapted to grip the fabric and increase the resistance to pulling it out of the clamp, can be formed about said holes, 5 in one operation and without additional cost.

The filler (Fig. 3) is an alloy or Babbitt-metal plate 4^a cast or formed with projecting rivet-shanks 5^a and 5^b projecting from its faces, adapted to register with the holes 10 3^a in the plate 1, and preferably conical, for convenience of assembling. Those shanks 5^a which will face the plunger of the press and penetrate the fabric, are made longer than those 5^b which merely are long enough to 15 extend through the plate-holes. The margin of the fabric, if it be woven wire, is preferably flattened and pierced with rivet-holes where it is intended to engage the clamp C and rivets 5. The filler 4^a is entered, with its short rivet shanks 5^b located 20 in the lower series of holes 3^a of the partly-folded plate 1, and thereupon the flattened edge of the fabric f is entered and its holes engaged with the upper rivet shanks 5^a of 25 the filler 4^a ; and the partly folded plate 1, together with the filler 4^a and the edge of the fabric f contained between its jaws, are passed between rolls or between the bed-plate and plunger of a press, the pressure of 30 which completes the clamp C by fully folding the plate 1, upsetting the rivet shanks 5^a and 5^b to form complete countersunk rivets 5, and flowing the metal of the filler 4^a into and therewith filling all and every 35 one of the holes or interstices of the fabric and between the plate-folds, bedding the strands of the fabric in the distributed metal of the filler and producing a bug-tight, fool-proof reliable fabric clamp, indestructible 40 by any usual treatment. Generally, rabbets, 6, of suitable depth, will be rolled in the plates 1 when they are manufactured; but the plates can be easily given this or any desired contour during the final operation, by 45 the use of appropriately formed rolls or dies.

As illustrated in Fig. 11, when we cut our clamp plates from suitable stock, we leave flaps, 7, on the ends, to one side of the axis. After the clamp C has been fully closed, as 50 above described, the rough edges of filler metal extruded from and projecting beyond the ends of the fold are suitably trimmed or squared up, and the end flaps are bent up square and close, so as to flow the projecting filler metal, left by the trimmer, into 55 all end-interstices, and are then folded and pressed tightly down upon the clamp and form clips 8, producing slightly finished ends, such as illustrated in Figs. 1 and 2. Where 60 the clamp is riveted these end flaps add little to the strength and stiffness of the clamp C, and could be dispensed with, but in un-riveted clamps C they resist clamp-opening stresses which might otherwise strain the

fold and ease the clamp; and we may, without much additional expense, provide similar but smaller clips 8^a along the margin of the clamp C, and relieving its jaws of opening stresses.

In Fig. 12 there is shown a form of our device that embodies therein, in combination with the previously noted filling means, a combination of mechanical lock therewith for maintaining the fabric against unusual or undue stress. The plate member 1 is shown as having on its lower fold a downwardly depending loop-like members 3^h , and the fabric member f having previously been flattened and an end 4^h being formed at right angles thereto, the said fabric is inserted into the space formed by the plate 1 and its lower member, thereby permitting a mechanical lock or engagement with the said plate. The filler may then be placed therein and the article subjected to proper pressure whereupon the member 3^h , with its contained fabric end, is forced over and upwardly, the filler conforming thereto and after completion of the operation the fabric is prevented, owing to its contour, from being withdrawn by any force short of breakage.

We claim as new and desire to protect by Letters Patent:—

1. The combination with a fabric clamp and a fabric, of a soft malleable metal filler for binding said clamp to said fabric by pressure being applied thereto.

2. A fabric clamp comprising a metal plate, marginal rivet holes in said plate and a softer metal filler, the plate adapted to form a clamp and the filler adapted to be flowed by pressure to fill internal interstices in the clamp and to fill the rivet holes and form rivets and hold the clamp closed.

3. A new article of manufacture, a flowable-metal filler for fabric clamps comprising a plate and rivet shanks on said plate.

4. A new article of manufacture, a flowable-metal filler for fabric clamps comprising a plate and series of oppositely outstanding rivet shanks on said plate.

5. A new article of manufacture, comprised of a pair of fabric clamps, a fabric therebetween, retaining means on said fabric, a flowable metal filler therefor, said fabric clamps being so formed as to engage the said fabric retaining means forming a fabric lock therewith.

6. As an article of manufacture, a soft malleable strip having conical projections on each side, which projections are longer on one side than on the other, said strip being adapted to be used as a filler and binder in fabric-clamping means.

7. As an article of manufacture, a malleable metal clamp-filler and fabric-binder strip having projections on each side there-

of, in combination with a harder metal clamp having perforations to correspond with the projections on said article.

8. As an article of manufacture, a malleable clamp strip having clamp interlocking means thereon, in combination with a fabric clamp having clamp strip interlocking means, whereby when pressure is applied

said strip and said clamp are formed into a unitary fabric clamping means.
